Issued Jan 27 1875.

UNITED STATES PATENT OFFICE.

GEORGE A. WELLS, OF TROY, NEW YORK, ASSIGNOR TO FULLER, WARREN & CO., OF SAME PLACE.

DESIGN FOR COOKING-STOVE.

Specification forming part of Design No. 8,044, dated February 2, 1875; application filed January 2, 1875.
 [Term of Patent 7 years.]

To all whom it may concern:

Be it known that I, GEORGE A. WELLS, of the city of Troy, in the county of Rensselaer and State of New York, have invented a new and original ornamental Design for Cooking-Stoves, of which the following is a specification, reference being had to the accompanying cut, print, or engraving of a cooking-stove having my said new design.

One part of this invention is the design for the oven-door panel, consisting of the representation of a quill-pen, A, shaped and arranged on the plain surface of the panel in an inclined position, and pointing downward and forward toward the lower front part of the panel, all so as to present substantially the same tasty and ornamental appearance on the side of a cooking-stove as is represented in the aforesaid engraving.

Another part of this invention consists of the design for the oven-door, composed of the representation of a quill-pen, A, shaped and

arranged in an inclined position in the plain surface of the panel, and the molding having a scalloped inner edging around the panel, all disposed so as to appear substantially as shown in and by the aforesaid print.

What I claim as my invention is—

1. The design for the oven-door panel, consisting of the representation of a quill-pen, A, shaped and arranged in the plain surface of the panel in an inclined position and pointing toward the lower front part of the panel, as shown and described.

2. The design for the over-door, composed of the plain-surface panel, the representation of a quill-pen thereon, and the border molding having a scalloped inner edging, all shaped and arranged as specified and shown.

GEORGE A. WELLS.
